[57] CLAIM

The ornamental design for a spoon or similar article, as shown and described.

DESCRIPTION

FIG. 1 is a front elevational view of a spoon or similar article showing my new design;

FIG. 2 is a side elevational view thereof, the side opposite being a mirror image thereof;

FIG. 3 is a rear elevational view thereof and;

FIG. 4 is a sectional view on an enlarged scale taken on line 4—4 of FIG. 1;

The distinguishing feature of my new design resides in the handle configuration.
